George E. Clegg.

INVENTOR:

Ethan Rogers.

By Knight Bros.

Atty's.

UNITED STATES PATENT OFFICE.

ETHIAN ROGERS, OF BALLSTON, NEW YORK, ASSIGNOR TO THE SIMMONS HARDWARE COMPANY, OF MISSOURI.

DESIGN FOR AN AX.

SPECIFICATION forming part of Design No. 21,253, dated December 22, 1891.

Application filed July 10, 1891. Serial No. 399,084. Term of patent 14 years.

To all whom it may concern:

Be it known that I, ETHAN ROGERS, a citizen of the United States, residing at Ballston, in the county of Saratoga and State of New York, have invented and produced a new and original Design for an Ax, of which the following is a specification, reference being had to the accompanying drawings, forming part thereof.

10 Figure I is a perspective view of my design. Fig. II is a transverse section on the line II II, Fig. I.

15 1 is the body of the ax, 2 the eye, and 3 the bit. On both sides of the ax, extending from about the center of the eye to the point of the

bit, are bevels 4, and across the front of the bit are bevels 5, that join the bevels 4. 6 is a central ridge on the sides of the ax. There is a clearly-defined line or low angle 7 8 8 7 extending along the inner edge of the bevels, 20 giving a marked distinction to the ax from those of ordinary finish.

What I claim is—

The design for an ax, substantially as herein shown and described.

ETHIAN ROGERS.

In presence of—

WILLIAM CAMPBELL,
WM. GRIFFIN.
